DESIGN FOR PANTIES OR SIMILAR ARTICLE

Dora Selver, New York, N. Y.

Application April 17, 1941, Serial No. 100,478

Term of patent 7 years

To all whom it may concern:

Be it known that I, Dora Selver, a citizen of the United States, residing at 350 Central Park West, in the county of New York, city of New York, and State of New York, have invented a new, original, and ornamental Design for Panties or Similar Article, of which the following is a specification, reference being had to the accompanying drawing, forming part thereof, and in which:

Fig. 1 is a front elevational view of panties, showing my new design;

Fig. 2 is a cross sectional view thereof, taken on line 2—2 of Fig. 1.

The back portion of my design is conventionally plain.

The characteristic feature of my design resides in the combination on the panties disclosed of the specific arrangement of wide and narrow stripes having eyeletted squares in staggered relationship on the front in association with the specific edging around the leg openings, all as shown.

I claim:

The ornamental design for panties or similar article as shown and described.

DORA SELVER.
